UNITED STATES PATENT OFFICE.

ANDREW J. UPHAM, OF Sycamore, assignor to HIRAM ELLWOOD, of De Kalb, Illinois.

BARBED-WIRE FENCE.

SPECIFICATION forming part of Letters Patent No. 284,261, dated September 4, 1883.

Application filed December 18, 1882. (No model.)

To all whom it may concern:

Be it known that I, ANDREW J. UPHAM, of Sycamore, in the county of De Kalb and State of Illinois, have invented certain new and useful Improvements in Barbed-Wire Fences; and I do hereby declare that the following is a full, clear, and exact description of the invention, which will enable others skilled in the art to which it appertains to make and use the same, reference being had to the accompanying drawings, and to the letters of reference marked thereon, which form a part of this specification.

My invention relates to a mode of placing wire barbs upon a fence-wire so that such barbs may remain fixed for the usual purpose of protecting such fence against the encroachments of stock, my object being to provide a cheap and effective fence-barb which will not be liable to displacement.

Figure 1 is a section of wire fence exhibiting my invention. Fig. 2 shows a portion of the upper and lower wires on a large scale.

AA are posts, through and between which are stretched the lower wire, b, and upper wires, c c. The wire b has two sides flattened to prevent the barb f from rotating. The wires c c show a slight indentation at the location of the barb f, for the same purpose; but the act of compressing the barb f upon a round wire, as hereinafter mentioned, will sufficiently flatten the wire at the location of the barb to prevent the rotating or shifting of the latter. The barb f is a short piece of wire, usually one or two sizes smaller than the fence-wire, pointed at each end, and placed upon the fence-wire by being passed around the latter, and having the ends of the barb crossed and bent back upon themselves. The barb is then, at the spot where its ends are crossed, forced down upon the fence-wire, so as to flatten or bring in line the aforesaid crossing of the ends of the barb and cause the points of the barb to

project in opposite directions in the same plane and at right angles with the fence-wire. 45 In order to cause each succeeding barb to point in a direction at right angles with its immediate predecessor, the wire may be twisted a half-revolution in the length of an interval between the barbs. This alternating of the 50 direction of the barb is generally considered necessary in barbed-wire fences to prevent stock from getting their heads and necks between the fence-wires, as well as to prevent them from crowding against the sides of the 55 fence.

The barbs f may be placed at right angles with each other in the first instance and the twisting of the wires dispensed with by the use of two machines or processes for placing 60 the barb; or if the single barb-wire is twisted with a fellow or binder wire, the result will probably be the same.

In practice I place and compress the barb f by machinery; but it may be done less speedily 65 by hand. In all cases I place a single barb rigidly upon a single wire.

A barb made and placed as shown is cheap and effective, can be painted with the fence-wire to prevent rust, furnishes a larger object 70 of sight than any barb now known formed from the same quantity of wire, and will last quite as long as the main wire.

I claim as my invention—

In combination with a fence-wire, substantially as specified, the encircling wire barb f, having its ends crossed and bent back upon themselves and firmly fixed in position by compression, as and for the purposes specified.

In testimony that I claim the foregoing as 80 my own I affix my signature in presence of two witnesses.

ANDREW J. UPHAM.
